CIGAR CONTAINER

John D. Conti, Philadelphia, Pa., assignor to Sylvania Industrial Corporation, Fredericksburg, Va., a corporation of Virginia

Application May 14, 1934, Serial No. 725,440

18 Claims. (Cl. 93—35)

This invention relates in general to containers and, in particular, to a tubular cigar container formed of a flexible, heat-fusible material and to correlated improvements in the process for forming an end closure for such container.

It has long been desired to provide cigar wrappers or containers formed of a non-fibrous material such, for example, as regenerated cellulose, with an end closure providing, on the one hand, protection from changing atmospheric conditions whereby the cigar is protected from excessive drying and, on the other hand, means for easily and safely removing the cigar without damage thereto.

When cigars are enclosed in pre-formed tubular containers such as the well known transparent, moistureproof tubes, the danger of damaging the cigar in removing it from the tube is not so acute on account of the fact that only one end of the cigar tube is sealed tightly, the other end usually being twisted or folded, thereby forming a closure which may be comparatively easily opened. On the other hand, when cigars are wrapped individually in a flexible, heat-fusible material, it is customary to seal the longitudinal seams by heat or a suitable adhesive and then provide each end of the wrapper with an end closure comprising inwardly tucked plicated sides forming with the upper and lower surfaces a multiply closure, the plies heretofore usually being held together by the fused coating located on the continuous surfaces. In addition, frequently, the flattened end is folded back and heat-sealed against the body of the container.

Smokers of cigars have adopted almost uniformly the practice of removing a cigar from its tubular container, either when pre-formed or when formed on the cigar, by pinching or pressing against one end of the cigar and pushing the other end through the end closure of the container. If the end closure has a tenacious seal, as commonly provided heretofore on wrapped cigars, very frequently the leaf wrapper of the cigar will be mutilated when the end of the cigar is forced through the seal. Furthermore, the cigar may be damaged by the excess pressure which must be applied to force it through the closure. With certain kinds of cigars such, for example, as blunt corona or panetela types, as distinguished from tapered perfectos, it is frequently almost impossible to remove the cigar from its wrapper by this method, this occasioning considerable annoyance on the part of the smoker.

It is a general object of the invention to pro-

vide a method of forming a container for cigars and like cylindrical objects whereby the cigar may be easily and rapidly forced through the container end seal without damage to the cigar.

It is another object of the invention to provide an improved process for wrapping cigars in flexible, heat-fusible materials and providing said wrapper with an end closure which may be easily ruptured by forcing the end of the cigar through the seal.

It is a more specific object of the invention to provide, as an article of manufacture, a container per se and also the combination of a tubular container formed of a moistureproof, flexible, heat-fusible material and a cigar contained therein, the container being provided with an end closure characterized by affording effective protection against changing atmospheric conditions and which may be easily broken by forcing the end of the cigar through the closure.

Other objects of the invention will in part be obvious and will in part appear hereinafter.

The invention accordingly comprises an article of manufacture possessing the features, properties and the relation of elements which will be exemplified in the article hereinafter described, and a process having the steps and the relation of steps, all as exemplified in the following detailed disclosure and the scope of the application which will be indicated in the claims.

For a more complete understanding of the nature and objects of the invention, reference should be had to the accompanying drawings in which:

Fig. 1 is a more or less diagrammatic side elevation of certain elements of an apparatus for forming an end closure on a tubular container formed of a flexible, heat-fusible material;

Fig. 2 is a view in perspective of the container of Fig. 1 illustrating the operation of the means for inwardly tucking the side walls of the container;

Fig. 3 is another view of the elements of the apparatus shown in Fig. 1 at a later time in the cycle of the sealing operation;

Fig. 4 is another view of the elements of the apparatus in Fig. 1 at a slightly later time than that shown in Fig. 3;

Fig. 5 is a view of the elements of the apparatus of Fig. 1 at a time slightly later than that shown in Fig. 4;

Fig. 6 is a bottom view of the flap folding and heat-sealing element shown in Figs. 1 to 5 inclusive;

Fig. 7 is a sectional view taken along line 7—7.

of Fig. 5 showing one embodiment of a sealing element made to carry out the process in accordance with the present invention;

Fig. 8 is a fragmentary top view of one embodiment of the container showing the areas of the end closure sealed by the sealing element of Fig. 7;

Fig. 9 is a cross sectional view of a second embodiment of the sealing element, showing it in sealing position on a wrapped cigar;

Figs. 10 and 11 are fragmentary top views of further forms of containers sealed in accordance with the present invention; and

Fig. 12 is an illustration of a method of removing the cigar from the novel container of the present invention.

The present invention is especially useful in connection with cigars which are individually wrapped in flat sheet material, but it is contemplated that features thereof may also be used with pre-formed tubular containers.

In the preferred practice of the invention, a cigar or like cylindrical object 1 is wrapped in a suitable sheet 2 of a flexible, heat-fusible material. The expression "heat-fusible material" is intended to include sheet material formed in whole or in part of, or combined with, a heat-fusible composition. In the now preferred embodiment, the wrapper consists of glycerinated sheets of cellulose hydrate regenerated from viscose which is combined with a heat-fusible, moistureproof coating. The cigar is placed with its longest axis parallel to the longest dimension of the sheet which is folded about the same and overlapped to form a longitudinal seam 3 which may be sealed by heat-sealing or by the use of a suitable adhesive applied in a known manner. The wrapped cigar now is brought to the position shown in Fig. 1 and the overhanging portions at one or both ends are subjected to the following sequence of operations:

Referring to Figs. 1 and 2, the opposing side walls of the overhanging portion at the end of the wrapper are inwardly tucked by a suitable element, after which the upper and lower surfaces are flattened upon the inwardly tucked sides to form a multi-ply closure as shown in Fig. 3. The element employed for pressing together the superposed plies is now removed and the flattened end is folded back on the body of the container by a suitable means as shown in Fig. 4. The folded, flattened end is then heat-sealed against the body of the container, heat being applied in laterally spaced areas A and A' adjacent the end, forming, in the illustrated instance, sealed and unsealed strips running lengthwise of the container, as shown in Figs. 7 and 8.

This sealing completes the essential wrapping operation although it is to be understood that the cigar or like cylindrical object may be subjected to other wrapping operations or enclosed in an additional container. The cigar or other object may be provided with a legend-bearing band either before or after the operation above described.

There are shown in Figs. 1 to 7 inclusive of the drawing certain elements of one embodiment of a suitable apparatus for carrying out the process of the invention. Referring to Fig. 1, the several elements of the end closing mechanism of the apparatus comprise means for inwardly tucking opposing side walls of the portion of the wrapper projecting beyond the end of the cigar, such means taking the form, for example, of a bifurcated Y-shaped tucker 10 of which the

branches 11 converge sharply to the shank 12 and which is reciprocated by suitable means (not shown) from the tucking position shown in Fig. 1 to the rest position shown in Fig. 3.

As the side tucker 10 withdraws from the position shown in Fig. 1, the upper and lower surfaces of the projecting wrapper are flattened onto the inwardly tucked portions by a suitable end presser and creaser comprising an upper male die or block 13 and a lower female die or block 14 which meet along the dotted line B-B and press the superposed plies between their opposing surfaces 15 and 16. The surfaces 15 and 16 are cut so as to crease the flattened end at a suitable point C adjacent the end of the cigar as shown in Fig. 3.

As the presser blocks 13 and 14 separate and move away from the flattened end, a folding and sealing element 17 is advanced to fold the flattened end onto the body of the container, 20 said element being actuated by a suitable mechanism (not shown) to reciprocate it from the rest position shown in Fig. 1 to the sealing position shown in Fig. 5. As illustrated in the several Figures 1 to 7 inclusive, one modification of this folding and sealing element consists of a shank 18 pivotally mounted at one end on a shaft 19 and provided at its opposite end with a folding and sealing head 20 heated by suitable means such, for example, 30 as an electric heating cartridge 21. The shank 18 rests upon a roller 22, the lower surface of the shank being provided with a contour such that as the shaft 19 is reciprocated horizontally, the folding and sealing head 20 will be caused 35 to move through the several positions shown in Figs. 1 to 5 inclusive.

The under side of the folding and sealing head 20 is provided with a groove 24, as shown in Figs. 6 and 7, or a plurality of grooves 124 as shown 40 in Fig. 9. Thus, when the head 20 contacts the flattened end of the wrapper as shown in Fig. 5, the flattened end is heat-sealed in laterally spaced areas A A, each separated by an unsealed gap, thus forming sealed and unsealed 45 strips running lengthwise of the container. In the now preferred embodiment, the sealed areas lie adjacent the outermost longitudinal edge of the flattened end and a central area is unsealed.

After the several end closing elements reach 50 the position shown in Fig. 5, the cycle is completed and all the elements then are withdrawn in order that a second wrapped cigar may be brought to the position shown in Fig. 1.

It is obvious that certain modifications in the 55 several end closing elements used to carry out the process of the invention may be made without transcending the scope of the invention. For example, if the flattened end is not to be folded back upon the body of the bag, the pressing 60 element may perform the sealing operation, in which case the block 13 and/or the block 14 may be provided with a heating element and one of the blocks grooved to seal the end in alternative areas forming sealed and unsealed strips 65 lengthwise of the container.

Further, separate elements may be provided for performing the operations of folding and of sealing. Moreover, the invention contemplates the use of adhesive and/or solvent and pressure 70 instead of heat and pressure in sealing, in which case the adhesive and/or solvent and pressure is applied to laterally spaced areas of the flattened end to form sealed and unsealed strips.

Thus, in Fig. 10 there is shown a container 2, 75

having a longitudinally sealed seam 3 and an overhanging end which is flattened back to line C' but is not folded back onto the container body. Here the flattened end is sealed, either by heat, adhesive or other suitable means, in laterally spaced areas A' A' which are separated from each other and from the seam 3 by unsealed gaps. If desired, the sealing of seam 3 may stop short of line C', further to facilitate ready opening of the container.

In Fig. 11 there is shown a further form of container having a flattened end which is folded back on the container body as in Fig. 8, and which is sealed thereto in a series of laterally spaced areas A''—A'', which are separated by unsealed gaps. These sealed areas may be obtained by use of the device shown in Fig. 9, or through use of an adhesive and/or a solvent or the like. In any case in which the latter forms of seal are used, the container may or may not be of heat-fusible material.

In the now preferred embodiment of the novel container, the longitudinal seam is not sealed throughout the entire length of the container, the seal terminating at a distance from the end closure as shown by the shaded area D of Figs. 8 and 11.

In each instance it will be noted that the invention contemplates provision of a tubular wrapper having a flattened end which is not sealed entirely across from side to side. Instead, sealing is restricted to laterally spaced areas separated by an unsealed gap, so that alternate sealed and unsealed portions are provided across the flattened end of the container.

It will be observed that by the present invention there has been provided a novel container for cigars or like cylindrical objects. To remove the cigar or other object from the container, one end of the container may be grasped by the fingers as shown in Fig. 12 and pressure applied to the end of the object inside of the wrapper so as to force the opposite end through the sealed end of the container. When the cigar or other object is forced through the end closure, the unsealed section of the longitudinal seam opens and permits the wrapper to expand freely as illustrated in Fig. 12. Thus the cigar may be removed from the flared wrapper without pinching the cigar out of shape or damaging its leaf wrapper.

I claim:

1. In a process of forming a container for cigars and like cylindrical objects, the steps comprising forming a tube of flexible sheet material, flattening the end of said tube, and sealing the flattened end in laterally spaced areas forming alternately sealed and unsealed strips lengthwise of the container.

2. In a process of forming a container for cigars and like cylindrical objects, the steps comprising forming a tube of flexible sheet material, flattening the end of said tube, and sealing the flattened end at the sides only, while leaving an unsealed gap at the center.

3. In a process of forming a container for cigars and like cylindrical objects, the steps comprising forming a tube formed of a flexible sheet of heat-fusible material and closing the end of said tube by flattening the end, and heat-sealing the flattened end in laterally spaced areas forming sealed and unsealed strips lengthwise of the container.

4. In a process of forming a container for cigars and like cylindrical objects, the steps com-

prising forming a tube formed of a flexible sheet of heat-fusible material and forming an end closure thereon by inwardly tucking opposing walls adjacent the end of the container, flattening the remaining walls on to said inwardly tucked portions and folding back and heat-sealing the flattened end on to the body of the container in laterally spaced areas forming alternate sealed and unsealed strips lengthwise of the container.

5. In a process of forming a container for cigars and like cylindrical objects, the steps comprising forming a tube having overlapping long edges from a sheet of flexible, heat-fusible material, sealing together the overlapping longitudinal edges, and forming an end closure thereon by inwardly tucking opposing walls and flattening the remaining walls on to said inwardly tucked portions, and folding and heat-sealing the flattened end on to the body of the container in laterally spaced areas forming alternately sealed and unsealed strips lengthwise of the container, the longitudinal seam being left unsealed for a distance from the end closure.

6. As an article of manufacture, a container for cigars and like cylindrical objects, comprising a flexible tubular container having a flattened end, said end being sealed at the sides only and having an unsealed gap at the center, said sealed end being readily broken open when pressure actuated from inside the container.

7. As an article of manufacture, a container for cigars and like cylindrical objects, comprising a flexible tubular container having an end flattened and folded back on to the body of the container, said flattened and folded end being sealed at laterally spaced areas separated by an unsealed space, said sealed end being readily broken open when pressure actuated from inside the container.

8. As an article of manufacture, a container for cigars and like cylindrical objects, comprising a flexible tube having its end flattened and sealed in laterally spaced areas forming alternately sealed and unsealed strips lengthwise of the container, said sealed end being readily broken open when pressure actuated from inside the container.

9. As an article of manufacture, a container for cigars and like cylindrical objects, comprising a flexible sheet formed into a tube having a longitudinal seam, the end of said tube being inwardly tucked at the sides and flattened, and the flattened end being sealed in laterally spaced areas forming sealed and unsealed strips lengthwise of the container, the longitudinal seam being left unsealed for a distance from the end of the container, said sealed end being readily broken open when pressure actuated from inside the container.

10. As an article of manufacture, a container for cigars and like cylindrical objects, comprising a flexible sheet of heat-fusible material formed into a tubular container having a longitudinal seam, the end of said tube being inwardly tucked at the sides and flattened, said flattened end being folded back and fused to the body of the container in laterally spaced areas forming sealed and unsealed strips lengthwise of the container, said sealed end being readily broken open when pressure actuated from inside the container.

11. As an article of manufacture, the combination of a container and a cigar contained therein, said container comprising a flexible tube having an end flattened, the flattened end be-

ing sealed in laterally spaced areas forming sealed and unsealed strips lengthwise of the container, the cigar being readily removable from the container by pushing the cigar through said sealed end.

5 12. As an article of manufacture, the combination of a container and a cigar contained therein, said container comprising a flexible sheet of material formed into a tubular container having a longitudinal seam, said tubular container having a flattened end, said flattened end being folded back and sealed in laterally spaced areas forming alternately sealed and unsealed strips lengthwise of the container, the cigar being readily removable from the container by pushing the cigar through said sealed end.

10 13. As an article of manufacture, the combination of a container and a cigar contained therein, said container comprising a flexible sheet of heat-fusible material formed into a tubular container having a longitudinal seam, said tubular container having a flattened end, said flattened end being folded back and fused to the body of the container in laterally spaced areas forming alternately sealed and unsealed strips lengthwise of the container, the cigar being readily removable from the container by pushing the cigar through said sealed end.

15 14. As an article of manufacture, the combination of a container and a cigar contained therein, said container comprising a flexible sheet of cellophane combined with a moistureproofing composition and formed into a tubular container having a sealed longitudinal seam, the end of said tubular container being inwardly tucked and said flattened end being folded back and sealed onto the body of the container in laterally spaced areas forming sealed and unsealed strips lengthwise of the container, the areas adjacent the longitudinal edges of the flattened end being sealed and the central area thereof being unsealed, and the longitudinal seam being un-

sealed for a distance from the end closure, the cigar being readily removable from the container by pushing the cigar through said sealed end.

16. A process for forming an end closure on a flexible, tubular container for cigars comprising sealing the flattened end of the container in laterally spaced areas forming alternately sealed and unsealed strips lengthwise of the container, said sealed end being readily broken open 10 when pressure actuated from inside the container.

16. A process for forming an end closure on a tubular container for cigars formed of a flexible sheet material comprising flattening the end 15 of the container and sealing the flattened end at the sides only while leaving an unsealed gap at the center, said sealed end being readily unsealed when pressure actuated from inside the container.

20 17. A process for forming an end closure on a tubular container for cigars formed of a flexible sheet of heat-fusible material comprising closing the end of the container, flattening the end and heat-sealing the flattened end in laterally spaced areas forming sealed and unsealed strips lengthwise of the container, said sealed end being readily unsealed when pressure actuated from inside the container.

25 18. A process for forming an end closure on a 30 tubular container for cigars formed of a flexible sheet material comprising inwardly tucking opposing walls adjacent the end of the container, flattening the remaining walls onto the inwardly tucked portions and folding back and sealing 35 the flattened end onto the body of the container in laterally spaced areas forming alternately sealed and unsealed strips lengthwise of the container, said sealed end being readily unsealed when pressure actuated from the inside of the 40 container.

JOHN D. CONTI.
